Term of patent 3½ years

(Cl. D34—15)

FIG. 1

FIG. 2

FIG. 3

The dominant features of my design reside in the portions shown in full lines.

The broken lines indicating projectiles are shown for illustrative purposes only.

I claim:

The ornamental design for a toy troop carrier vehicle, substantially as shown and described.
